THREAD DRYING APPARATUS

Lorin A. Corey, Cleveland Heights, and Thomas S. Mayner, Willoughby Township, Lake County, Ohio, assignors to Industrial Rayon Corporation, Cleveland, Ohio, a corporation of Delaware

Application November 27, 1946, Serial No. 712,476

6 Claims. (Cl. 34—153)

1

This invention relates to an apparatus for drying thread or the like and, more particularly, to an apparatus having a generally circular heated periphery over which the thread or the like is adapted to pass.

In the manufacture of thread or the like, for instance rayon, by the continuous process a plurality of treating steps are performed on the thread in a rapid and sequential manner. One of these steps constitutes the drying of the thread. It is, of course, desirable to rapidly, uniformly and effectively dry the thread continually at a rate comparable to that of the other treatments performed on the thread. To effect such drying, there should be a rapid and constant transfer of heat to the thread from the surface of a reel over which it travels.

Thread-drying reels are usually heated by fluids such as steam, hot water, hot oil or hot gases. These heating fluids are utilized in either open-ended or closed type thread-drying devices. Generally, the closed type of drying device is preferable as it is more economical, efficient, and safer to use. Although such thread-drying devices are advantageous, they are not as efficient as they could be because the distances from their interior wherein the heating fluid circulates to the thread on the surface of the device are greater than desired, the distances causing certain heat losses. It is an obvious fact, of course, that the longer the distance through which heat must be transmitted the greater is the heat loss. If a predetermined temperature is to be maintained at the surface of the reel or of the drying device, then any heat lost because of distance must be compensated for by increasing the temperature of the heating fluid or increasing the heating fluid circulation. Heat losses can be materially reduced by decreasing the heat transfer distance to a reel surface, and the efficiency of an internally heated drying reel improved.

It is the purpose of this invention to provide a thread drying apparatus wherein the heat transfer distance is minimized so that heat losses are advantageously and materially reduced. Advantageously, the invention will be described in connection with a cantilever type thread drying, thread advancing reel wherein the circulating heating fluid is made to circulate in close proximity to the thread. Such a reel is shown in the Corey Patent No. 2,413,217. Passages are provided in thread-bearing members of such a cantilever type reel to conduct a heating fluid substantially adjacent to the thread; the passages being in such close proximity to the thread that there

occurs a minimum loss of heat before the thread is reached. The drying reel comprises a thread-bearing periphery of longitudinal bar or tubular thread-bearing members having passages through which a heating medium is continuously circulated. With the passages located within the thread-bearing bars, the distance through which the heat is transferred to the thread is merely the thickness of the thread-bearing wall over which the thread travels. Such a construction advantageously provides for a rapid transfer of heat, a low heat loss, and a lower heat content in the fluid used.

The invention and its advantages will be more readily understood by reference to the following description and the attached drawing where:

Figure 1 represents in elevational cross section, a cantilever type thread-storing, thread-advancing drying reel;

Figure 2 is a section of the drying reel of Figure 1 taken along line 2—2; and

Figures 3 and 4 represent modifications of the reel of Figure 1.

Referring to Figures 1 and 2, the reel shown is formed of two generally cylindrical reel members 10 and 11 which may be made of metal or of non-metallic heat conducting material. Reel member 10 is mounted concentrically on the shaft 12 to rotate therewith. The reel member 10 comprises a cylindrical chamber 15 having a periphery of a plurality of longitudinal bar members 17. The chamber 15 is formed by enclosing the cylindrical section with end closing members 18 and 19 which are mounted on shaft 12. The end closing members are frictionally bound to the shaft by means of seals 20, 21, thus affixing the reel member 10 to the shaft 12. The frictional binding of the closures is effected by drawing a cap 23 against the seal 21 and front closure member 18 by means of a threaded bolt 24 in the end of the shaft 12, compressing both the seals 20, 21 between the closure members and the shaft. This construction not only binds the reel member 10 to the shaft but it also makes the chamber 15 fluid tight.

Reel member 11 also has a periphery formed of a plurality of longitudinal bar members 28. The bar members of both reel members 10, 11 are positioned in an interdigitating relation, the two sets forming a unitary, generally cylindrical, thread-storing, thread-advancing reel. The bar members 28 of the reel member 11 are supported at one end by means of a flange 29 and at the other end by means of a reinforcing circular ring 30. The flange 29 is, in turn, fixed by means of

bolts 32 to the flange of hub member 31. Hub member 31 is adapted to rotate on a pair of anti-friction bearings 33, 34 mounted on a generally circular eccentric and askew member 35. The skewed eccentricity of the member 35 positions the reel member 11 in an askew and offset relation to the concentric reel member 10. This relationship causes the reel when rotated to advance thread over its surface in a number of generally helical turns.

As shown in Figure 1, the reel member 11 is mounted so as to rotate on the eccentric member 35. The concentric reel member 10 which is fixed to the shaft 12, drives or is adapted to drive the eccentric reel member 11 through frictional bar contact or advantageously through a complementary gear set in order to prevent frictional contact between the longitudinal bar members. The eccentric reel member 11 is then, advantageously driven by means of the complementary gears 49 and 41 which are attached to the reel members 10 and 11 respectively. Gear 40 mounted on reel member 10 is thus adapted to drive reel member 11 through gear 41.

The longitudinal thread-bearing bar members 17 of reel member 10 are provided with passages 42 for the circulation of a heating fluid. The passages 42 are made when the bar members are extruded or by boring the bar members lengthwise, the boring being done in a manner so as to provide a minimum desirable upper wall thickness. The ends of the passages 42 can be closed off by means of studs 43. At substantially the ends of passages 42, other connecting passages 44 and 45 are made or bored generally downwardly through the longitudinally bar members in order to effect communication with passages 46 and 54 in the end closures 19 and 18, respectively. Thence passages 46 communicate with inlet openings 48 in shaft 12 and passages 46 with the interior of chamber 15. Openings 48 in the shaft 12 serve as inlets for the heating fluid into the passages 42 of the reel member 10. The reel interior or chamber 15 is exhausted through shaft openings 55.

Heating fluid under pressure is then adapted to circulate in the longitudinal passages 42 of the bar members 17, thence into chamber 15 of reel member 10 and out of it through shaft 12 exhaust openings 55 into the shaft exhaust passage 52. Since the passages 42 in the bar members 17 are under the periphery of the reel member 10, there is a substantially immediate transfer of heat to the thread advancing over the reel. The thickness of the wall between the passage 42 and the thread carrying surface can, of course, be such so as to only provide sufficient strength to carry the thread. The bar members 28 of the eccentrically positioned reel member 11 are, of course, heated by radiation from the bar members 17.

As stated, the heating fluid is exhausted from the reel chamber 15 through openings 55 and the core passage 52 of the shaft 12. The heating fluid, instead of first being accumulated in the chamber 15, can be exhausted at once from the passages 42 by joining the exhaust opening 55 with passages 54. This can be done by enclosing the exhaust openings with the closure member 18 in a similar manner as the inlet openings 48 are enclosed by the closure member 19. It may be desirable, however, to first accumulate the heating fluid in the cylindrical chamber 15 before exhausting it through openings 55 and the shaft passage 52. This temporary retention of the

heating fluid serves to heat up the reel interior and to thereafter maintain its temperature.

Figures 3 and 4 show how the reel construction can be modified to eliminate or avoid the use of the chamber 15. In Figure 3, the front closure member 18 is altered in its design and is made of such thickness so as to have bored therethrough a passage 54 which communicates with the shaft exhaust openings 55. The closure member 18 thus encompasses the shaft openings 55 in a similar manner as rear closure member 19 encompasses the shaft inlet openings 48. If it is desired to prevent any heat loss to the interior of the reel member 10, the inside of the reel may be insulated or the cylindrical portion may be constructed of any desirable heat insulating material. The heat loss, however, is very readily stabilized in that direction so that insulation may not be necessary.

Where the thickness of the vertical section of the longitudinal thread bearing member 17 will not permit the use of a single passage 44 or 45 of the required diameter for the circulation of the heating fluid, then additional passages such as 25 passages 60 and 61 may be provided in order to permit an adequate flow of fluid.

The chamber 15 may be entirely eliminated and at the same time the weight of the reel reduced by constructing the unit reel member 10 of a light 30 material such as sheet aluminum and aluminum tubing, or of stainless steel. As shown in Figure 4, the closures 18 and 19 may be formed as hollow structures of a sheet material having the required thickness to provide the necessary strength. 35 Being hollow, the closure members provide adequate space for the admission and the exhaust of the heating fluid. The thread bearing bar members 17 may be formed of tubular sections which are fastened and sealed into position in 40 the closure members 18, 19. The closures 18 and 19 as hereinbefore described may be mounted directly over the inlet and exhaust openings 48 and 55 of the shaft 12 encompassing them in order to provide for a fully enclosed circulation 45 of the heating fluid within the reel.

There is, thus, provided a more efficient thread-storing, thread-advancing drying reel which may be readily applied to other methods for manufacturing rayon than the continuous process. Furthermore, such a drying reel is also adapted for the drying of textile materials other than rayons.

We claim:

1. An apparatus for drying thread or the like comprising a reel embodying two interdigitating 55 sets of bar members forming a generally circular periphery over which the thread or the like is adapted to pass, means for actuating the bar members to advance the thread in a helical path, one of said sets of bar members being hollow and 60 serving as heating fluid conductors for the flow of a heating fluid therethrough, and a heating fluid inlet and outlet means to said heating fluid bar member conductors.

2. An apparatus for drying thread or the like 65 comprising a reel embodying two interdigitating sets of bar members disposed in an offset and inclined relation to each other forming a generally circular periphery over which the thread or the like is adapted to pass, one of said sets of bar members being hollow serving as heating fluid conduits for the flow of a heating fluid therethrough, and a heating fluid inlet and outlet means to and from said hollow bar member conduits.

3. An apparatus for drying thread or the like

comprising a reel embodying two interdigitating sets of bar members disposed in an offset and inclined relation to each other forming a generally circular periphery over which the thread or the like is adapted to pass, one of said sets of bar members forming the periphery of a hollow chamber, said bar members of said set having passages throughout substantially their lengths, end closures for said chamber, a shaft on which said reel is mounted, said shaft having conduits for supplying and exhausting a heating fluid to and from said set of hollow bar members, and said end closures having passages communicating with said shaft heating fluid conduits and the passages of said set of bar members.

4. An apparatus for drying thread or the like comprising a reel embodying two interdigitating sets of bar members disposed in an inclined relation to each other forming a generally circular periphery over which the thread or the like is adapted to pass, one of said sets of bar members having passages substantially throughout their lengths forming the periphery of a generally cylindrical chamber, one end of said passages communicating with the interior of said chamber, end closures for said chamber, passages in one of said end closures, a shaft on which said reel is mounted, said shaft having conduits for supplying and exhausting a heating fluid to and from said bar member passages, said end closure passages joining one of said shaft conduits with said bar member passages, the other of said shaft conduits communicating with said hollow chamber.

5. An apparatus for drying thread or the like comprising a reel embodying two interdigitating sets of bar members, forming a generally circular periphery over which the thread or the like is adapted to pass, one of said sets of bar members being hollow, a shaft supporting said reel having passages for the inlet and exhaust of a heating

fluid to said set of hollow bar members, and hollow end supporting means for said set of hollow bar members, said hollow end supporting means enclosing said shaft passages and communicating with both the hollow bar members and said shaft passages.

6. A cantilever type thread storing, thread advancing, drying apparatus comprising a reel embodying two interdigitating sets of bar members disposed in an offset and askew relation to each other forming a generally circular periphery over which thread or the like is adapted to pass, a shaft having a heating fluid inlet and outlet on which said reel is mounted, one of said sets of bar members being hollow, said set of hollow bar members having shaft supporting means at substantially their ends for supporting them concentrically of said shaft, shaft supporting means for supporting said other set of bar members in an offset and askew manner and from one end only, and said supporting means of said hollow bar members having passages communicating with said shaft heating fluid inlet and outlet and said hollow bar members.
